(57) **CLAIM**

The ornamental design for a knife sheath with clip for longitudinal attachment to a strap, as shown and described.

DESCRIPTION

FIG. 1 is a rear perspective of the knife sheath, showing the transverse clip in an open position.

FIG. 2 is a rear view perspective of the knife sheath showing the transverse clip in a closed position.

FIG. 3 is a front perspective of the knife sheath with the transverse clip in a closed position.

FIG. 4 is a front elevation view of the knife sheath, showing longitudinal attachment along a shoulder strap.

FIG. 5 is a front elevation view as in FIG. 4, shown without the optional knife; and,

FIG. 6 is a front perspective as shown in FIG. 3, shown without the optional knife.

The broken line showing of a knife in the drawings is included for the purpose of illustrating only and forms no part of the claimed design.
